CONCENTRIC INTAKE AND EXHAUST VALVES FOR INTERNAL COMBUSTION ENGINES AND THE LIKE

Donald Edward Olson, Lake Geneva, Wis.

Application March 17, 1954, Serial No. 416,915

16 Claims. (Cl. 123—75)

The present invention relates to intake and exhaust valves for internal combustion engines and the like, to an arrangement of intake and exhaust valves in concentric relation and, particularly, to a concentric arrangement of intake and exhaust valves for four cycle internal combustion engines and the like wherein the admission valve is relatively freely mounted for movement in response solely to fluid pressures acting thereon.

In conventional four cycle internal combustion engines, the intake, inlet, or admission valve and the exhaust valve provided in each engine cylinder are both poppet valves, each comprising a stem slidably guided in the engine block or head and a circular valve head for closing the respective port. Both valves are positively driven by engine operated cam means and are normally retained in closed position by very stiff or strong springs overcome only upon cam actuation of the valves. In view of the fact that two circular ports are provided in each cylinder, it is apparent that each port must be of a diameter less than one half of the diameter of the cylinder unless special design is resorted to. In recent years, progress in metallurgy, in the petroleum art and in engine design has accommodated long desired increases in engine compression ratios to as high as 8.25 to 1. In the high compression range, the size of the engine cylinder and combustion chamber must be decreased in relation to the amount of gas admitted to the chamber. However, the necessary compactness of the combustion chamber cannot be attained in relation to valve port size in many conventional motor designs, such as the L-head engine, since decrease in combustion chamber size necessarily leads to a decrease in port size. This dilemma has practically eliminated the L-head engine from further power increases and has forced engine designers to investigate and experiment with specialized combustion chamber and piston designs. Many designers and manufacturers have now adopted hemispherical or pill shaped combustion chambers and intake and exhaust valves set at various angles in the chambers. By recourse to overhead valves, angularly related to one another and to the combustion chamber, and a hemispherical combustion chamber, the problem has been eased somewhat. However, even with such design, a definite limit is imposed. Each year, designers, in endeavors to increase compression ratios and engine power, are being forced more and more to depart from the above design and to adopt combustion chambers of parabolic shape and to employ domed pistons, with the dome on the piston progressively increasing in height until design possibilities are exhausted.

It is an object of the present invention to provide a novel approach to engine design and, particularly, to provide a new approach for the design of engines of increased horsepower and increased compression ratios, by means of a novel arrangement of the intake and exhaust valves in each engine cylinder.

Specifically, it is a primary object of the present invention to provide a novel engine valve and head or block design wherein the engine exhaust port and exhaust valve

2

may be generally conventional, but wherein the intake or admission port is disposed in generally concentric relation to the exhaust port and surrounds the exhaust port, and wherein the intake or admission valve is concentric with the exhaust valve and surrounds the same in spaced relation thereto.

The arrangement of the ports and valves as provided according to the present invention accommodates, for example, opening of substantially the full area of one end wall of the combustion chamber or cylinder as intake and exhaust ports, whereby a greater area of a given cylinder is made available for porting than could possibly be attained with individual poppet valves as has been conventional.

According to the present invention, in the simplest embodiment thereof, the combustion chamber and engine piston are of simplified or basic design and present, merely, flat opposed end surfaces, as contrasted to the complicated parabolic chambers and domed pistons presently in commercial use. The flat surface of the combustion chamber is provided substantially coaxially of the cylinder with a circular exhaust port and the engine block or head is formed to define an exhaust valve seat encircling the exhaust port. A conventional poppet valve may suitably be employed to control the exhaust port. Radially outwardly of the exhaust port, the engine block or head is formed to define an annular admission or intake port surrounding the exhaust port in spaced substantially concentric relation thereto. At the inner and outer margins of the admission port, the engine head or block is formed to define a pair of concentric valve seats. An annular ring valve, comprising preferably only a metallic annulus, is provided to control the intake port, the same being adapted to seat against the concentric valve seats and surrounding the exhaust valve in radially spaced concentric relation thereto.

In comparison to conventional designs, the valve port and valve arrangement of the present invention affords a substantially greater port area to cylinder area ratio than can be attained with conventional designs. For example, in a conventional engine having a 3 1/4 inch diameter cylinder and assuming 1/4 inch clearance between the sides of the cylinder and the ports and between ports, the engine could be provided, at a maximum, with 1 1/4 inch diameter exhaust and intake ports, each affording a port area of approximately 1.23 square inches. According to the present invention, for the same diameter cylinder, the exhaust port, merely as an example and not as a suggested design, could be 2 inches in diameter to afford a port area of 3.14 square inches and the intake port could have an inner diameter of 2 1/4 inches and an outer diameter of 3 inches to afford a port area of approximately 3.09 square inches—an increase of more than 250% in port area over conventional designs for the given cylinder diameter. Analyzing this capability in terms of accommodating a decrease in cylinder volume for a given port area to accommodate increase in the compression ratio and power of an engine, assume that a port area of 1.23 square inches is desired. From the above, it is obvious that a conventional simplified design would necessarily employ two circular ports 1 1/4 inches in diameter, which would necessitate a cylinder diameter of 3 1/4 inches. According to the present invention, however, the central circular exhaust port would have a diameter of 1 1/4 inches, and the annular intake or admission port could have an inner diameter of 1 1/2 inches and an outer diameter of 1 15/16 inches to afford intake and exhaust ports each having an area of approximately 1.23 square inches. Thus, the cylinder would have to be only 2 3/16 inches in diameter—a reduction of approximately 33% in cylinder diameter and of approximately 55% in cylinder area over the conventional design. Accordingly, it is seen that

the present invention, by affording a novel port and valve arrangement, opens a new avenue of approach to internal combustion engine design to accommodate compression ratios heretofore unattainable. Also, the invention accommodates increased compression ratios in engines, such as the L-head engine previously referred to, that were regarded practically as being incapable of further power and compression ratio increases. Furthermore, the present invention affords the above advantages in a particularly economical manner as will appear more fully hereinafter.

Having considered the aspect of engine design problems as regards compression ratios, it is of interest now to consider the problems involved in providing means for operating the valves. As noted above, the valves employed in conventional designs are poppet valves firmly biased to closed position by strong springs to be actuated to open position solely by means of engine operated cams and associated drive apparatus. Since present commercial engine design involves overhead valves set at an angle in the combustion chamber, it is apparent that many difficulties are encountered in operatively connecting the valve stems to the conventional engine operated camshaft. The rocker arms and push rods employed in the operative connection or transmission between the overhead valves and the camshaft presents substantial inertia, which is a deterrent to proper valve opening and which is a factor that must be combated as regards valve closing by the use of very substantial or heavy valve springs. Even so, floating of the valves cannot be eliminated entirely, which is a serious disadvantage since valve opening and closing cannot be accurately controlled. To avoid this disadvantage, recourse may be had to double overhead camshafts, but the cost involved is so great as to negative practical recognition of the suggested solution.

In addition to suffering problems with respect merely to the connection of the valves and camshaft, designers also encounter problems of valve timing. A motor designed for high speed operation, if it is to be successful, must utilize a cam contour such as will hold the intake or admission valve open for a relatively long period in the cycle of engine operation. When a motor with such cam contour is running at slow speed, however, there is, at the start of the compression stroke of the piston, a reverse movement of air or the gaseous combustible mixture through the still open intake port due to the fact that the incoming column of the combustible mixture lacks sufficient momentum at that speed to resist or overcome the tendency to reverse flow, which disrupts the performance of the carburetor and results in a substantial loss of the combustible charge. This causes the engine to lack power and smoothness at lower speeds. On the other hand, a motor designed to run at slow speed will have a cam contour such as will open the intake valve for a relatively short interval in relation to the cycle of engine operation, with the result that the motor will lack power at high speed.

It is an object of the present invention to eliminate the problems of mechanical valve operation, connection of the valve to a camshaft, valve floating, cam contour and mechanical valve timing by mounting the intake or admission valve relatively freely, and entirely independently of mechanical actuating means, to accommodate intake valve actuation solely in response to fluid pressures acting thereon, whereby the valve is opened and closed solely in response to engine demands.

A further object of the invention is the provision of an intake or exhaust valve assembly constructed in accordance with the foregoing, wherein the intake or admission valve in its preferred form consists solely of a metallic annulus. Due to the fact that the intake port as described hereinbefore is an annular port, all that is required to close it is an annulus. Furthermore, since the valve is to be relatively freely mounted, no stem is required therefor. Accordingly, the present invention affords a par-

5 ticularly simplified intake valve for internal combustion engines.

According to the present invention, as will be appreciated from the foregoing, the engine head or block defines an annular intake port and a pair of concentric valve seats disposed, respectively, adjacent the inner and outer margins of the port. The annular intake valve is of a size to close the annular port and is adapted to seat upon the said concentric seats. Due to the fact that the port will be of a relatively small radial dimension, and due to the seating of the valve on seats adjacent each margin thereof, the valve need be only a relatively thin washer. If desired, the central portion of the annulus may be rigidified by a web, but even so the annulus completely eliminates the heavy or bulky explosion resisting center and stem of the conventional poppet valve. Consequently, the annular ring valve is very light in weight, only a small fraction of a poppet valve of equal capacity. Furthermore, the valve when opened accommodates flow at both margins or peripheries thereof, whereby the valve need open only a limited extent to admit large volumes of gas.

Because of its light weight and short stroke, which reduces its inertia substantially to zero, the annular intake valve of the present invention, as incorporated in a four cycle internal combustion engine or the like, is ideally suited to actuation by means of the fluid pressures to which it is exposed. In a four cycle engine, the piston in its downward movement on the intake stroke tends to establish a lower pressure in the cylinder than exists in the intake manifold, whereupon the pressure in the manifold is effective to open the valve to accommodate entry, as induced by the engine piston, of air or a combustible charge. On the upward compression stroke, the piston increases the pressure in the cylinder over that in the manifold, whereupon the valve is moved to closed position. As will be apparent, the valve will be maintained closed during the majority of the compression stroke, during combustion and during the expansion and exhaust cycles, whereupon the operation above described will be repeated. Due to the rapidity of piston movement, variations in pressure in the cylinder, to which the valve should respond, are quite sharp to insure proper actuation of the valve. Accordingly, it will be appreciated that the valve of the present invention depends for its operation solely on the pressure differential between the intake manifold and the engine cylinder. At low speeds, the valve will automatically adapt itself to a relatively short admission interval and the engine will idle or lug smoothly and with optimum power. Upon high speed operation, the gust or rapidly moving column of gas induced to flow at high speed past the intake valve, due to the high speed descent of the piston on its intake stroke, will have sufficient momentum to hold the valve open longer against compression than at low speeds, thus to duplicate in valve actuation the movement theoretically induced by the contour of an imaginary high speed cam. Accordingly, the valve of the present invention is operable solely in response to the demands of the engine to accommodate an exceptionally wide variation in engine speed and to afford smooth performance and optimum power at all speeds. In combination with a generally conventional mechanically actuated poppet type exhaust valve, the freely mounted annular intake valve provides an engine valve assembly assuring optimum engine performance.

In addition to opening a new avenue of engine design, accommodating increased compression ratios and affording an intake valve operable solely in response to engine demand, the present invention promotes highly economical overall engine design. Specifically, the present invention accommodates reduction in cylinder diameter, eliminates all mechanical actuating means for the intake valve and accommodates simplification of the exhaust valve actuating means, whereby the engine block and/or head may be reduced in size and simplified very readily.

It is also an object of the present invention to provide a highly simplified stop means in a valve and head construction as defined hereinbefore, wherein the stop means is disposed in spaced relation to the seat of the annular ring valve positively to define limits of valve movement.

A further object of the invention is the provision of combined stop and locating means, provided in accordance with the immediately foregoing, wherein the means includes portions engaging the peripheral margin of the annular valve to locate or center the valve with respect to its seats, and portions spaced from the valve seats and engageable with the surface of the valve to define the open position of valve movement.

A still further object of the invention is the provision, in a valve and head construction of the character above defined, of spring means of a relatively weak nature adapted at least to counterbalance the weight of the annular ring valve, the spring means preferably being slightly stronger than the strength required to counterbalance the weight of the valve, whereby the spring means normally biases the valve lightly toward its seat. While not absolutely essential, the spring means is assistive at low speed starting and does not in any way interfere with optimum valve operation in response to engine demands at higher speeds.

In conventional engine designs, the poppet valves, as above noted, do not operate well at high speed unless the valve springs are exceptionally stiff or strong. This stiff springing leads to substantial impact of the valve in seating and to rapid wear of the valve, valve seat, tappet and cam. In contrast, the ring valve of the present invention, due to its light weight, short stroke and large seating area, will not pound against the seat, and thus is not subject to rapid wear. Furthermore, the valve does not suffer limitations due to weight and stiff springing, so that the valve is operable and positive in action at higher speeds than heretofore thought possible. While the ring valve of the invention will not pound with substantial impact against its seat and the stop means defining the open limit of valve movement, it may prove advisable in some designs to incorporate damping means for the valve to eliminate the possibility of pounding, particularly in the valve opening direction, and to insure against vibration or oscillation of the valve. In this respect, it is an object of the present invention to incorporate damping means for the annular valve in the valve and head construction described above. Such means may take the form, simply, of the spring means referred to hereinbefore, or specially formed and mounted damping means.

In particular, it is an object of the present invention to provide, in a head and valve construction as above described, combined damping, centering, stop and spring means for the annular valve. In a preferred form, such combined means comprises a cam mounted for rotation in the head or block means of the engine on an axis disposed at right angles to the axis of movement to the annular valve. The cam presents a cam surface facing and engageable with the valve and curved to define a point of contact with the valve progressively spaced from the valve seat. A spring operatively associated with the cam normally biases the high spot thereof into engagement with the valve to bias the valve toward its closed position. As the valve is opened, the cam is required to rotate against the force of the spring, thus damping the opening movement of the valve. When the low point on the cam engages the valve, cam rotation necessarily ceases, whereby the cam defines a stop limiting opening movement of the valve. Also, the combined means includes a mounting for the cam, which mounting may include portions continuously engaging the margin of the valve to center the valve with respect to its seat. Thus, a simple unit incorporates all the controls desired for the ring valve. The cam, due to the cam surface thereof, converts any tendency towards pounding, vibration, or oscillation into a rolling action, and imparts

rotary movement to the valve as the engine is running, which distributes wear, keeps the valve and its seat polished and free of carbon, and maintains optimum seating.

As will be appreciated, despite reference hereinbefore to combustible charges, the present invention has special adaptability to four cycle internal combustion engines, whether the same be of the spark or injection ignition type. However, it would appear that the provision of cam type means as described above would tend to detract from or destroy the optimum configuration of the combustion chamber, in either type of engine, and thus tend to negative the advantages to be attained by the valve construction of the invention. In particular, it would appear that the presence of cams and the like protruding into the combustion chamber would lead to inefficient ignition and explosion propagation. To the contrary, it is an object of the present invention to utilize the cam means as above described for purposes promoting more efficient ignition and explosion propagation. Specifically, it is an object to so shape and locate the cams, and to locate the ignition means, the spark plugs or injectors, strategically with respect to the cams so that the explosion progresses or propagates with a swirling or whirlpool motion, or some other desirable propagation pattern. In a preferred embodiment, three cams are provided in circumferentially spaced relation in the combustion chamber and a spark plug is disposed adjacent each cam in non-radial relation to the cylinder, each cam being provided with a face defining a portion of a helix facing toward the adjacent spark plug, whereby, upon ignition, the explosion propagates in a somewhat helical pattern to insure complete and uniform explosion of the combustible charge in the combustion chamber. With injectors in a diesel engine, control of the propagation pattern can also be effected by means of the cams. As will be appreciated, such preferred embodiment of the invention affords the further advantage in high compression ratio engines of insuring a uniform, but very rapid, substantially instantaneous explosion of the entirety of the combustible mixture in the combustion chamber.

Other objects and advantages of the present invention will become apparent in the following detailed description of preferred embodiments of the invention.

Now, in order to acquaint those skilled in the art with my invention and the manner of making and using the invention, I shall describe, in connection with the accompanying drawings, several preferred embodiments of the invention and preferred manners of making the same.

In the drawings, wherein like reference numerals indicate like parts:

Figure 1 is a fragmentary vertical cross section of one cylinder of an internal combustion engine including a first embodiment of the head and concentric arrangement of the intake and exhaust valves of my invention, the view being taken substantially on line 1—1 of Figure 2;

Figure 2 is a bottom view of the head and valve arrangement of the first embodiment of the invention, the view being taken substantially on line 2—2 of Figure 1;

Figure 3 is a perspective view of preferred stop and centering means as employed in the first embodiment of the invention;

Figure 4 is a view similar to Figure 2 of a second embodiment of my invention;

Figure 5 is an exterior end view of one of the cam means of the Figure 4 embodiment of the invention;

Figures 6, 7 and 8 are inside end views of one of the cam means of the Figure 4 embodiment of the invention, showing the sequence of cam movement upon opening movement of the ring valve; and

Figure 9 is a fragmentary vertical section of the simplest preferred embodiment of the invention.

Referring now to the drawings, and particularly to Figures 1 and 2, there is shown therein a portion of an internal combustion engine comprising a block 10 defining a cylinder 12 within which a piston 14 is mounted for

reciprocation in a conventional manner. An engine head 16 is attached to the block 19 and has therein a chamber 18, which together with the cylinder 12 defines a combustion chamber into which one or more spark plugs 20 extend, suitably through the side wall of the head. For convenience, the engine block 19 and head 16 are referred to hereinafter generically as block means. The engine represented is a four cycle internal combustion engine of the spark ignition type, the piston thereof having the four usual strokes or cycles of intake, compression, 10 expansion and exhaust.

The engine head 16, as shown, preferably comprises a metallic casting having cooling water passages 22 therein, as is conventional, an intake manifold or manifold extension 24, and an exhaust manifold or manifold extension 26, the manifolds 24 and 26 opening to the opposite sides of the head for communication, respectively, with generally conventional intake and exhaust manifolding covers (not shown), as will be appreciated by those skilled in the art. The exhaust manifold 26 is curved inwardly and downwardly within the block means or head 16 to terminate, in the embodiment disclosed, in a circular exhaust port 28 disposed substantially coaxially of the cylinder 12. About the port 28, the head 16 is machined or otherwise finished to provide a valve seat 36. The port 28 is adapted to be controlled by means of a conventional poppet type exhaust valve 32 including a stem 34 slidably mounted in the block means and a circular head 36 of a diameter larger than the port 28 and disposed to the cylinder side thereof, the head being adapted to engage the seat 36 adjacent its peripheral margin to close the exhaust port. As is customary, the poppet valve includes an explosion resisting reinforced central portion 38. The valve stem 34 is slidably mounted in a bearing guide 40 which is press fitted or otherwise suitably secured in the block means or head in axial alignment with the cylinder 12. The valve stem 34 extends through the bearing guide 40 to the exterior of the head 14 and adjacent its outer end carries an abutment in the form of a split conical washer 42 seated in a circumferential recess in the stem. The washer 42 defines a seat for a spring retainer 44, and a pair of springs 46 and 48 are confined between the head 16 and the retainer 44, as is conventional with poppet valves, normally to bias the valve to closed position with the head 36 of the valve firmly engaging the valve seat 36. The exhaust valve is adapted to be positively actuated by any usual drive arrangement, such as from an engine driven cam shaft (not shown) through a push rod assembly (not shown) and a rocker assembly including a shaft 50 and a tappet arm 52 engageable with the upper exposed end of the valve stem 34. As will be appreciated, the valve 32 is opened against the bias of the springs 46 and 48 by the drive means in timed relation to the movement of the piston 14 to accommodate discharge of the gaseous products of combustion, in the path indicated by arrows in Figure 1, on the exhaust stroke or cycle of the piston 14. As thus far described, the construction of the head, to afford the exhaust port and manifold, and the assembly of the exhaust valve and actuating means are generally conventional, except for the location of the port and valve substantially coaxially of the cylinder 12.

The intake manifold 24 is formed in the engine block means or head 16 to surround the portion of the exhaust manifold 26 adjacent the exhaust port 28 in generally annular form and is separated from the exhaust manifold by walls means and a generous water jacket 22, the jacket serving to cool the exhaust manifold and exhaust valve seat and to prevent undue transmission of heat to the intake manifold. The intake manifold 24 communicates with the combustion chamber 18 and cylinder 12 by means of an annular intake or admission port 54 disposed in radially spaced concentric relation to the exhaust port 28. The inner margin of the annular port 54 is spaced radially outward of the margin of the exhaust port and

the outer margin of the port 54 is spaced radially inward of the peripheral wall of the combustion chamber 18. Adjacent each margin of the port, the block means or head 16 is machined or otherwise finished to afford a pair of concentric circular intake valve seats 56 and 58. The intake port 54 is adapted to be controlled by an annular intake or admission valve 60 having an inner diameter less than the inner diameter of the port 54 but greater than the outer diameter of the head 36 of the exhaust valve 32, and an outer diameter greater than the outer diameter of the port 54, but less than the diameter of the combustion chamber, the valve being adapted to engage the valve seats 56 and 58 to close the port 54. The valve 60 may comprise, simply, as is shown in Figure 1, a thin metallic washer or annulus of extremely light weight. At the outer margin of the valve 60, the peripheral wall of the combustion chamber 18 is spaced from the valve, or is formed to be spaced substantially from the valve, to accommodate flow of gases from the intake manifold past both margins of the valve. Accordingly, the valve need open only a short distance to accommodate maximum capacity flow through the intake port 54. Due to its short stroke and light weight, the valve is ideally suited to actuation solely in response to engine demands as a function of the pressures acting thereon, which is a primary object of the present invention.

The intake valve 60 is disposed within the engine cylinder and/or combustion chamber entirely independently of the exhaust valve 32 and no means are provided for mechanically actuating the valve, the same being at least relatively freely mounted for movement in response to pressures acting thereon. In the case of a four cycle internal combustion engine, the valve is thus caused to be moved on the downward, intake stroke of the piston 14, as a result of the pressure in the intake manifold 24 exceeding that in the cylinder 12 and combustion chamber 18, to open the valve to accommodate entry of fresh gases to the cylinder and chamber. Upon the upward compression stroke of the piston, the pressure in the combustion chamber exceeds that in the intake manifold and the intake valve is closed to accommodate full compression of the gases. Upon explosion of the gases and the expansion stroke of the piston, the valve is held to its seat by the high pressure in the cylinder and combustion chamber, and also upon the upward exhaust stroke of the piston 14 due to the relatively high pressure in the cylinder. Since the valve 60 seats uniformly on two seats and bridges only a relatively short radial space, the valve need be only a relatively thin washer and yet will readily withstand the shock of the explosion. At low speed, the valve 60 will automatically be actuated to provide a relatively short open interval thus to accommodate entry of the proper charge for efficient engine operation at that speed. At higher speeds, the valve will automatically be opened in the manner above described, but the inflowing column of gas will have such momentum as to retain the valve open a relatively long interval after the compression stroke commences, thus to insure a complete charge of gas in the cylinder necessary to high speed operation. At any engine speed, the valve will be responsive to the pressures acting thereon to open and close exactly in conformity to the demands of the engine for optimum performance. Since the valve is light weight and has a short stroke, it has substantially no inertia and can build up little momentum and, therefore, is immediately responsive to critical variations in the pressure differential between the intake manifold 24 and the cylinder 12 and combustion chamber 18. In short, the valve will operate at substantially any given speed in accordance with the valve operation theoretically produced by an engine operated cam specifically designed for that speed. Accordingly, it is to be appreciated that the valve 60 of the present invention operates in optimum timing with the engine piston to insure desired engine performance at all speeds.

While the annular valve 60 of the invention, as above noted, has little inertia and is operable at substantially all engine speeds in an optimum manner, I prefer to improve still further on the arrangement as above described by providing spring means, indicated generally at 62, at least to counterbalance the weight of the annular ring valve and preferably to bias the same slightly toward closed position, but not necessary to a completely closed position. Counterbalancing the weight of the valve reduces its inertia, and normal disposition of the valve adjacent or lightly in engagement with its seats assists in proper valve operation at very low speeds and in starting of the engine. In the Figure 1 embodiment of the invention, the spring means 62 comprises a plurality of small-tension springs 64, connected to the valve 60 by means of tabs 66 formed integrally with the valve, and to hooks 68 formed integrally with the head 16 within the intake manifold 24. The springs 64, together, are of a strength only slightly in excess of the strength required to counterbalance the valve 60 and, accordingly, bias the valve toward its seats and, preferably, lightly into engagement with its seats, thus to afford the advantages noted above with respect to engine operation. While the springs afford assistance to valve operation, the valve nevertheless is substantially freely mounted in the engine for movement solely in response to engine demands, since the spring are not strong enough to negative or in any way detract from the above described optimum engine operation.

As will be appreciated, the annular ring valve 60 cannot be entirely freely mounted in the cylinder, since the valve, if not restricted, would tend to travel with the engine piston. However, the valve must not be constricted, since it is necessary that the same be free to move independently in response to engine demands. In other words, means must be provided to limit opening movement of the valve without otherwise interfering with the valve. To this end, I provide stop means, indicated generally at 70, disposed in axially spaced relation to the admission port 54 to limit opening movement of the annular admission valve. Also, since space is provided according to the invention at both margins of the valve to accommodate maximum admission of gases, it is preferable to provide locating means to center the valve with respect to its seats. In the embodiment of the invention shown in Figures 1 to 3, the stop means and locating means are incorporated in a single assembly comprising, as particularly shown in Figure 3, a stop member 72 and a locating member 74. Preferably, a plurality of such assemblies are provided, as indicated at 70 in Figure 2, in circumferentially spaced relation about the combustion chamber. The member 72 comprises a bolt adapted to be threaded into a tapped bore provided in the peripheral wall of the combustion chamber to extend substantially radially from the wall into the chamber and into the path of movement of the valve 60. The bolt is provided with a head and the head is preferably machined to present a flat stop surface 76 for engagement by the valve to limit opening movement of the valve. The locating member 74 comprises a tubular spacer element adapted for the passage therethrough of the bolt and having a radial, tab-like extension 78 presenting a rearward surface conforming substantially to the configuration of the combustion chamber 18 and a flat forward face engageable with the outer peripheral margin of the valve 60. In assembly, the locating members 74 are disposed in the combustion chamber in general alignment with the respective radial bore adapted for the reception of a stop member 72. The valve 60 is then placed in the chamber 18, the members 74 being of such length as to have the flat surfaces thereof disposed immediately adjacent the outer margin of the valve to guide the valve to its seats substantially in centered relation to the admission port 54. The stop members are then inserted in the chamber, through the respective tubular member

74 and threaded into the respective bore in the chamber and tightened to dispose the surface 76 thereof in facing relation to the lower surface of the valve, whereupon the assembly is completed, the valve 60 is properly positioned in the chamber 18, the valve is centered with respect to its seats, and positive limits of valve movement are provided, all in a highly economical and practical manner.

From the foregoing, it will be appreciated that the present invention affords a particularly advantageous valve arrangement for internal combustion engines and the like, wherein valve operation is completely and perfectly responsive to engine demands, even though those demands vary widely from low to high speed operation, rather than being dependent upon and subject to the serious shortcomings of mechanical drive means and mechanical design of cams and the like, which can be of optimum efficiency for only one speed. Also, the valve, due to its independency, is not subject to the speed limitations imposed upon mechanically operated valves in conventional designs, thus opening the way to higher speed engines than heretofore contemplated. Furthermore, the concentric arrangement of the valves accommodates substantial increases in compression ratios by accommodating a greater port area to cylinder area ratio than heretofore possible with conventional designs. A few examples of this capability have been pointed out in the introductory portion of the present specification. To repeat one of these examples, assume the desired condition of intake and exhaust ports having an area of 1.23 square inches. In a conventional design, two circular ports, each 1 1/4 inches in diameter would have to be provided, which would result in a cylinder diameter of approximately 3 1/4, allowing 1/4 inch clearances. According to the present invention, the exhaust port would have a diameter of 1 1/4 inches and the annular intake port could have an inner diameter of 1 1/2 inches and an outer diameter of 1 5/16 inches, whereupon the combustion chamber adjacent the valve 60 would be of a diameter of approximately 2 5/16 inches. Thus, the present invention results in a decrease over a conventional design of 33% in combustion chamber diameter and 55% in combustion chamber area. Furthermore, as shown in Figure 1, the cylinder of the engine, according to the present invention, need not be of as great a diameter as that of the combustion chamber adjacent the valve, but could, for example, be of the same diameter as the outer diameter of the valve. This arrangement would accommodate a total decrease in cylinder area over conventional designs of approximately 63%. From these figures, it is apparent that the present invention accommodates tremendous increases in compression ratios and horsepower output in internal combustion engines.

In view of the capability of the present invention to afford very substantial increases in compression ratios, engine power and engine speed, it is contemplated that present ignition systems may prove inadequate to cope with the advances afforded. In view of this factor, I prefer to incorporate a plurality of spark plugs 20, or fuel injectors, or the like, in each combustion chamber, rather than the single unit conventionally provided. For example, as shown in Figure 2, a pair of ignition units or spark plugs 20 may be provided in diametrically opposed relation, the same extending substantially radially into the combustion chamber through the side walls of the block means or head 16.

In addition to affording substantial advantages with respect to engine operation, engine speed, and compression ratios, the present invention accommodates and provides substantial economies in the design, manufacture, and assembly of the engine block means. Normally, it would be expected to obtain substantial advantages in engine and valve operation and increases in compression ratios only by substantially increasing the cost and complexity of the engine. Directly the contrary is true with

the present invention, since the advantages afforded by the invention are all accomplished as a result of a very high degree of simplification. Since all mechanical operating means for the intake valve are eliminated, it is obvious that a substantial saving is achieved with respect to the mechanical components and assembly steps required in the manufacture of an engine. Secondly, the capability of the invention substantially to increase compression ratios with highly simplified piston and combustion chamber designs, eliminates many of the costly and complicated manufacturing steps involved in making most of the present day high compression engines. Third, the capability of the present invention to reduce combustion chamber and cylinder size affords a further saving in material, and fourth, the provision of only a single valve to be mechanically actuated accommodates simplification and ready assembly of the actuating means for this valve. Furthermore, the total result of the foregoing reductions in cost and complexity is to reduce the size and intricacy of the engine block means, as including the block 10 and head 16, thus to afford an engine having greater capabilities than conventional engines and at the same time one that is much more economically produced than previously proposed designs. Accordingly, it is to be appreciated that the present invention affords substantial advances in engine design, particularly with respect to engine operation, power, performance, and economy.

As pointed out hereinbefore, the annular ring valve 60 of the invention is light weight and has a short stroke, whereby its inertia is reduced nearly to zero and whereby it cannot build up substantial momentum. Due to the fact that the valve has double seating at 56 and 58, the same will not "slam" closed and little wear of the valve seats and valve will be occasioned. However, in the opening direction, it may in certain instances be desirable to provide means eliminating any possibility of valve vibration and "slamming" or substantial impact of the valve against its stops. In Figures 4 to 8, I have shown preferred means for accomplishing this result, wherein the means affords, in a single assembly, stop means of the nature previously described, spring means of the nature previously described, locating or centering means of the nature previously described, means for damping movements of the valve, and means affording a predetermined pattern of explosion propagation to insure efficient ignition of the fuel in the combustion chamber. The embodiment of the invention as shown in Figures 4 to 8 is very similar to that previously described, with the exception of the combined means provided therein, and accordingly, parts similar or identical to those previously described have been indicated by the same reference numerals.

In Figures 4 to 8, the combined means or damping means of the invention is indicated generally at 80 and a plurality of the means or assemblies are provided in circumferentially spaced relation about the combustion chamber. Each unit comprises a mounting member 82 in the form preferably of a split sleeve inserted in and extending through a radial bore provided in the block means or head 16. A cam member 84 including a shaft portion 86 is rotatably mounted in the member 82 with the cam portion thereof disposed within the engine combustion chamber. The shaft portion 86 is preferably provided with a tapped bore therein opening to the rearward end thereof and adapted for the adjustable reception of a set screw 88, the set screw assuming, when set, a fixed relation to the shaft and cam. To the exterior of the block means or head 16, a clamp 90 is secured, suitably by a screw 92, to the extending portions of the split sleeve 82, and the clamp includes a boss from which a pin 94 extends. The pin 94 constitutes a mounting for the free or outer end of a flat, helical, torsion spring 96, in the nature of the watchmakers' hair spring, the other end of which is connected to the set screw 88,

whereby the spring is effective to exert a rotary force on the cam 84. As both the clamp 90 and the set screw 88 are adjustable, the rotary force exerted on the cam 84 by the spring 96 may be varied quite widely, the more readily effected adjustment being that of the set screw 88.

The cam 84 presents a first cam surface 98 opposed to the face of the ring valve 60 and engageable therewith. The surface 98 is formed to present, as the cam rotates counterclockwise as viewed in Figures 6 to 8, a point engageable with the valve disposed progressively further away from the valve seats, thus to accommodate valve opening. When the cam is moved to dispose the lowest point on the surface 98 thereof in engagement with the valve, the cam cannot rotate further and thus constitutes a stop defining the open limit of valve movement, as shown in Figure 8. Accordingly, the unit 80 is first the stop means of the character hereinbefore defined with reference to numeral 70. The spring 96, as will be appreciated from Figures 5 to 8, normally biases the cam 84 in a clockwise direction as the same is viewed in Figures 6 to 8, thus to dispose the high point of the cam surface 98 in engagement with the valve as shown in Figure 6. The cumulative effect of the springs 96 of the three units 80 is to only slightly more than offset the weight of the valve 60, whereby the valve is counterbalanced and lightly biased toward its seat. Accordingly, the unit 80 is secondly a spring means of the nature previously described with reference to numeral 62. Furthermore, the adjustability of the spring 96 accommodates variations in valve responsiveness by the simple expedient of an adjustment from the exterior of the engine. With respect to centering the ring valve 60 in relation to its seat, the mounting members 82 may each present a face to the interior of the combustion chamber engageable with the outer peripheral margin of the valve to center the same in much the same manner as described with reference to numeral 74.

Upon downward movement of the valve 60 on the intake stroke of the piston as hereinbefore described, the valve will engage the cam surfaces 98 and cause the cams 84 to rotate against the bias of the springs 96. Thus, the springs 96 will cushion the valve and prevent substantial impact of the valve with its stops, and will eliminate any possibility of valve vibration. Also, the rotary movement of the cams transforms the straightline movement of the valve to a smooth rolling action to eliminate "slamming." Accordingly, it is to be appreciated that the units 80 damp the ring valve 60 to insure optimum operation thereof. Furthermore, the rotation of the cams imparts a rotary impetus to the valve to cause the same to rotate by small increments within the engine, which rotary movement eliminates the possibility of one cam constantly engaging the same point on the valve and wearing a "pocket" therein, results automatically in cleaning of the surface of the valve and the cam surfaces 98 to insure optimum valve operation, and renders the valve automatically self-cleaning and self-polishing, the valve in turn polishing its seats and the cams to insure optimum performance and uniform wear of the valve.

In addition to the surface 98, the cam 84 is curved generally laterally of the curvature of the surface 96 to define a second cam surface 100 disposed generally at right angles to the plane of the valve 60. In this embodiment of the invention, the spark plugs 20, which may suitably be of the same number as the units 80, are each disposed adjacent a unit 80, preferably in non-radial relation to the cylinder and in non-parallel relation to the respective unit, with the inner end thereof opposed to the cam surface 100 of the respective unit 80. The cam surface 100 is formed in a predetermined manner to coact with the spark plug 20, fuel injector, or other ignition means, to impart a desired propagation pattern to the explosion ignited by the ignition means. For example, as is shown in Figure 4, the cam surface 100 of each cam 84 may be

curved to define a portion of a helical pattern having its focus at the center of the engine piston, and the spark plug 20 is opposed to such surface, whereby, upon energization of the plug to ignite the combustible charge in the combustion chamber, a helical, swirling, or whirlpool propagation pattern is imparted to the explosion to insure proper, complete and efficient ignition and expansion of the combustible charge. Accordingly, the damping means, instead of detracting from optimum chamber design, actually contributes to the overall design and affords another particular advantage of the present invention. Also, the provision of a plurality of ignition devices insures uniform, instantaneous ignition and explosion of the fuel in the combustion chamber.

In view of the foregoing, it is to be appreciated that the damping means 30 of the present invention affords substantial advantages in conjunction with the concentric valve arrangement of the invention and incorporates in a single and economically produced unit the several operating characteristics enumerated hereinbefore. The spring damper improves flexibility of the timing of the valve and accommodates wider opening of the valve than permanently located stops. Also, the adjustability of the spring affords the distinct possibility of altering the speed and torque characteristics of the engine by a simple adjustment at the side of the engine block means.

Referring now to Figure 9, a simplified embodiment of the invention is shown wherein all springs and dampers have been eliminated. The embodiment is generally similar to that of Figure 1 and parts similar to those previously described have been indicated by the same reference numerals. In addition to elimination of the spring means, the stop means 70 has been simplified, the same comprising merely a plurality of pegs or pins 102 pressed, fitted or otherwise secured in the engine block means or head 16 to project radially into the path of movement of the annular ring valve 60. A degree of centering or locating of the valve may be attained with these stops by providing a stepped outer end portion on the pins, as is shown. The annular valve 60 in this embodiment of the invention comprises, instead of a thin flat washer as previously described, an integral annulus including a plate portion 104 and a reinforcing web 106. The web 106 decreases in width from the plate portion 104 into the annular admission port 54 to serve the triple functions of reinforcing the valve, at least partially centering the valve 60 with respect to its seats 56 and 58, and defining a smooth path for the inflow of gases to eliminate any obstructions to flow and to insure against undue turbulency in the incoming stream of gases.

From the foregoing, it will be appreciated that the present invention, in its various embodiments, affords substantial advantages in internal combustion engine design, in increased compression ratios and power output, in optimum valve operation and in high speed operation of the valve. While the foregoing embodiments have been described principally in relation to internal combustion engines of the spark ignition type, it is clear that the invention is very advantageously employed in injection type engines. To the present, four cycle Diesel engines have not been able to compete with the gasoline engine in light weight machinery due to an inability to introduce adequate air into the cylinders while maintaining the high compression ratios necessary to compression ignition. The ability of the present invention to solve such problem is apparent. Furthermore, the present invention is not limited in application to internal combustion engines, but has complete applicability to compressors, positive displacement pumps and the like, such as a two cycle pump including a high pressure responsive outlet valve and the admission valve of the invention disposed in concentric relation to the outlet valve.

In addition, the invention has been described hereinbefore with reference to simplified engine and combustion chamber design, which of course, is one advantage of the

invention in that high compression ratios and increased horsepower can be attained with the simplest combustion chamber and piston designs. However, it is to be appreciated that the invention is applicable as well to specialized designs, such as those referred to in the introductory portion of the specification.

Further, it is to be borne in mind that the basic arrangement of the present invention relates to the concentricity of the two valves and is not necessarily limited to circular and annular arrangements.

While I have described what I regard to be preferred embodiments of my invention, it will be appreciated that various changes, rearrangements and modifications may be made therein without departing from the scope of the invention, as defined by the appended claims.

I claim:

1. An admission and exhaust valve assembly for internal combustion engines and the like having at least one cylinder, comprising an exhaust valve having a valve head, and an admission valve comprising a thin annulus surrounding said exhaust valve head in spaced concentric relation thereto, said admission valve being independent of said exhaust valve and being at least relatively freely mounted to move in response to pressure variations in the cylinder with which associated.

2. An admission and exhaust valve assembly for four cycle internal combustion engines having at least one cylinder, comprising a positively driven exhaust valve having an operating stem and a generally circular valve head, and a generally annular admission valve consisting of a thin annulus disposed concentrically about said exhaust valve head in spaced relation thereto, said admission valve being independent of said exhaust valve and being at least relatively freely mounted to move in response to pressure variations in the engine cylinder with which associated.

3. In a four cycle internal combustion engine or the like having block means defining at least one cylinder, an exhaust port in the block means opening into the cylinder,

40 40. an intake manifold in the block means, and an intake port in the block means surrounding the exhaust port in spaced concentric relation thereto and establishing communication between the intake manifold and the cylinder, a valve assembly comprising a positively driven exhaust valve having an operating stem slidably mounted in the block means and a head secured to said stem to the cylinder side of the exhaust port to close the exhaust port, and an intake valve consisting of a thin annulus surrounding said exhaust valve head in spaced concentric relation thereto to close the intake port, said intake valve being at least relatively freely mounted in the cylinder independently of said exhaust valve to the cylinder side of the intake port to move in response to variations in the pressure differential between the intake manifold and the cylinder, whereby the intake port is opened and closed solely in accordance with engine demands.

45 45. 4. In an internal combustion engine or the like having block means defining at least one cylinder, an exhaust port in the block means opening into the cylinder, an intake manifold in the block means and an intake port in the block means surrounding said exhaust port in spaced concentric relation thereto and establishing communication between the intake manifold and the cylinder, a valve assembly comprising an exhaust valve having a head to

50 50. close the exhaust port, an intake valve comprising a relatively thin annulus surrounding said exhaust valve head in spaced concentric relation thereto to close the intake port, said intake valve being at least relatively freely mounted in the cylinder independently of said exhaust valve to the cylinder side of the intake port to move in response to variations in the pressure differential between the manifold and the cylinder, whereby the intake port is opened and closed solely in accordance with engine demands, and spring means operatively associated with the

block means and said intake valve normally to bias said intake valve lightly toward the intake port.

5. In an internal combustion engine or the like having block means defining at least one cylinder, an exhaust port in the block means opening into the cylinder, an intake manifold in the block means, and an intake port in the block means surrounding the exhaust port in spaced concentric relation thereto and establishing communication between the intake manifold and the cylinder, a valve assembly comprising an exhaust valve having a head to close the exhaust port, an intake valve comprising a relatively thin annulus surrounding said exhaust valve head in spaced concentric relation thereto to close the intake port, said intake valve being at least relatively freely mounted in the cylinder independently of said exhaust valve to the cylinder side of the intake port to move in response to variations in the pressure differential between the manifold and the cylinder, whereby the intake port is opened and closed solely in accordance with engine demands, and stop means mounted on the block means within the cylinder in spaced relation to the intake port to limit opening movement of said intake valve with respect to the intake port.

6. In an internal combustion engine or the like having block means defining at least one cylinder, an exhaust port in the block means opening into the cylinder, an intake manifold in the block means, and an intake port in the block means surrounding the exhaust port in spaced concentric relation thereto and establishing communication between the intake manifold and the cylinder, a valve assembly comprising an exhaust valve having a head to close the exhaust port, an intake valve comprising a relatively thin annulus surrounding said exhaust valve head in spaced concentric relation thereto to close the intake port, said intake valve being at least relatively freely mounted in the cylinder independently of said exhaust valve to the cylinder side of the intake port to move in response to variations in the pressure differential between the manifold and the cylinder, whereby the intake port is opened and closed solely in accordance with engine demands, spring means operatively associated with the block means and said intake valve to counterbalance the weight of said intake valve and normally to bias said intake valve lightly toward the intake port, and stop means carried by the block means within the cylinder in spaced relation to the intake port to limit opening movement of said intake valve with respect to the intake port.

7. In an internal combustion or the like having block means defining at least one cylinder, an exhaust port in the block means opening into the cylinder, an intake manifold in the block means, and an intake port in the block means surrounding the exhaust port in spaced concentric relation thereto and establishing communication between the intake manifold and the cylinder, a valve assembly comprising a positively driven exhaust valve having an operating stem slidably mounted in the block means and a head secured to said stem to close the exhaust port, an intake valve consisting of a thin annulus surrounding said exhaust valve head in spaced concentric relation thereto to close the intake port, said intake valve being at least relatively freely mounted in the cylinder independently of said exhaust valve to the cylinder side of the intake port to move in response to variations in the pressure differential between the manifold and the cylinder, whereby the intake port is opened and closed solely in accordance with engine demands, and a plurality of circumferentially spaced stops extending radially inward from the peripheral wall of the cylinder in spaced relation to the intake port to limit opening of said intake valve.

8. In an internal combustion engine or the like having block means defining at least one cylinder, an exhaust port in the block means opening into the cylinder, an intake manifold in the block means and an intake port

in the block means surrounding the exhaust port in spaced concentric relation thereto and establishing communication between the intake manifold and the cylinder, a valve assembly comprising an exhaust valve having a head to close the exhaust port, an intake valve surrounding said exhaust valve head in spaced concentric relation thereto to close the intake port, said intake valve being at least relatively freely mounted in the cylinder to the cylinder side of the intake port to move in response to variations in the pressure differential between the manifold and the cylinder, whereby the intake port is opened and closed solely in accordance with engine demands, and locating means mounted on the block means and at least partially engageable with said intake valve to center said intake valve in relation to the intake port and to define a path of intake valve movement related to the intake port.

9. In an internal combustion engine or the like having block means defining at least one cylinder, an exhaust port in the block means opening into the cylinder, an intake manifold in the block means and an intake port in the block means surrounding the exhaust port in spaced concentric relation thereto and establishing communication between the intake manifold and the cylinder, a valve assembly comprising an exhaust valve having a head to close the exhaust port, an intake valve surrounding said exhaust valve head in spaced concentric relation thereto to close the intake port, said intake valve being at least relatively freely mounted in the cylinder to the cylinder side of the intake port to move in response to variations in the pressure differential between the manifold and the cylinder, whereby said intake port is opened and closed solely in accordance with engine demands, and a plurality of centering and stop units disposed in circumferentially spaced relation about the peripheral wall of the cylinder, said units each including centering portions engageable with the marginal edges of said intake valve to center said intake valve in the cylinder and with respect to the intake port, said units each including stop portions projecting radially inward from the peripheral wall of the cylinder in spaced relation to the intake port engageable by said intake valve to limit opening movement of said intake valve.

10. In an internal combustion engine or the like having block means defining at least one cylinder, an exhaust port opening into the cylinder, an intake manifold in the block means and an intake port in the block means surrounding the exhaust port in spaced concentric relation thereto and establishing communication between the intake manifold and the cylinder, a valve assembly comprising an exhaust valve having a head to close the exhaust port, an intake valve surrounding said exhaust valve head in spaced concentric relation thereto to close the intake port, said intake valve being at least relatively freely mounted in the cylinder to the cylinder side of the intake port to move in response to variations in the pressure differential between the manifold and the cylinder, whereby the intake port is opened and closed solely in accordance with engine demands, and spring biased cam means movably mounted on the block means and operatively associated with said intake valve normally to bias said intake valve toward the intake port, the spring means of said cam means being effective to exert a force on said intake valve only slightly in excess of that required to counterbalance the weight of said intake valve, whereby said intake valve when moving in response to engine demands is lightly damped by said cam means.

11. In an internal combustion engine or the like having block means defining at least one cylinder, an exhaust port in the block means opening into the cylinder, an intake manifold in the block means and an intake port in the block means surrounding the exhaust port in spaced concentric relation thereto and establishing communication between the intake manifold and the cylinder, a valve assembly comprising an exhaust valve having a head to close the exhaust port, an intake valve surrounding said

exhaust valve head in spaced concentric relation thereto to close the intake port, said intake valve being at least relatively freely mounted in the cylinder to the cylinder side of the intake port to move in response to variations in the pressure differential between the manifold and the cylinder, whereby the intake port is opened and closed solely in accordance with engine demands, a plurality of cams extending radially inwardly from the peripheral wall of the cylinder, said cams being rotatably mounted on the block means, and torsion spring means operatively associated with each of said cam means normally to rotate the same in a given direction, said cams each including a cam surface engageable with one surface of said intake valve and curved progressively to accommodate movement of said intake valve away from the intake port upon rotation of said cams against the bias of said spring means, said spring means normally biasing said cams to move said intake valve toward the intake port, said cams damping the movements of said intake valve.

12. In an internal combustion engine as set forth in claim 11, means associated with said cams and said spring means accommodating adjustment of said spring means to vary the damping characteristics of said cams.

13. In an internal combustion engine as set forth in claim 11, ignition means adjacent each of said cams, each of said cams including portions adjacent the respective ignition means to impart a predetermined propagation pattern to the explosion ignited by said ignition means.

14. An admission and exhaust valve assembly for internal combustion engines and the like having at least one cylinder, comprising an exhaust valve having a valve head, an admission valve disposed concentrically about and surrounding said exhaust valve head, said admission valve being independent of said exhaust valve and being freely mounted to move in response to pressure variations in the cylinder with which associated, and locating means at least partially engageable with said admission valve to locate said admission valve in predetermined relation to the cylinder.

15. An admission and exhaust valve assembly for internal combustion engines and the like having at least one cylinder, comprising an exhaust valve having a valve head, an admission valve disposed concentrically about the surrounding said exhaust valve head, said admission valve being independent of said exhaust valve and being freely mounted to move in response to pressure variations in the cylinder with which associated, and at least one locating and stop unit including a portion engageable with the edge of said admission valve to locate said admission valve in predetermined relation to the cylinder and a stop portion engageable with one surface of said admission valve to limit movement thereof.

16. An admission and exhaust valve assembly for internal combustion engines and the like having at least one cylinder, comprising an exhaust valve having a valve head, an admission valve disposed concentrically about and surrounding said exhaust valve head, said admission valve being independent of said exhaust valve and being freely mounted to move in response to pressure variations in the cylinder with which associated, and spring biased cam means operatively associated with said admission valve normally to bias said admission valve in one direction, said spring biased cam means being effective upon movement of said admission valve in the opposite direction lightly to damp the movement of said admission valve.
